No. 36,620.

Patented November 10, 1903.

UNITED STATES PATENT OFFICE.

EDWARD BENDHEIM, OF NEW YORK, N. Y.

DESIGN FOR A HANDKERCHIEF.

SPECIFICATION forming part of Design No. 36,620, dated November 10, 1903.

Application filed September 25, 1903. Serial No. 174,678. Term of patent 7 years.

To all whom it may concern:

Be it known that I, EDWARD BENDHEIM, a citizen of the United States, and a resident of New York city, State of New York, have invented a new, original, and ornamental Design for Handkerchiefs, of which the following is a specification.

The figure of the drawing shows my design for a handkerchief in elevation.

What I claim as new, and what I desire to secure by Letters Patent, is—

The ornamental design for a handkerchief as shown.

In witness whereof I have hereunto set my hand in the presence of two witnesses.

EDWARD BENDHEIM.
